UNITED STATES PATENT OFFICE.

LUCKEY C. DAVIS, OF BOLEY, OKLAHOMA.

GUN AND PROJECTILE THEREFOR.

1,304,857.

Specification of Letters Patent. Patented May 27, 1919.

Application filed January 7, 1918. Serial No. 210,651.

To all whom it may concern:

Be it known that I, LUCKEY C. DAVIS, a citizen of the United States, residing at Boley, in the county of Okfuskee, State of Oklahoma, have invented certain new and useful Improvements in Guns and Projectiles Therefor, and I do hereby declare the following to be a full, clear, and exact description of the invention, such as will enable others skilled in the art to which it appertains to make and use the same.

This invention relates to new and useful improvements in guns.

One object of the present invention is to provide a novel gun which is especially adapted for discharging chain shot for the purpose of destroying wire entanglements, or other obstructions.

Another object is to provide a novel projectile for use in connection with the gun.

Other objects and advantages will be apparent from the following description when taken in connection with the accompanying drawing.

25 In the drawing:

Figure 1 is a plan view of a gun made in accordance with my invention.

Fig. 2 is a transverse sectional view taken on the line 2-2 of Fig. 1.

30 Fig. 3 is a horizontal longitudinal sectional view taken through the gun.

Fig. 4 is a perspective view of the projectile removed from the gun.

Fig. 5 is a perspective view of a cartridge 35 used in connection with the gun.

Fig. 6 is an enlarged horizontal sectional view through the cartridge.

Referring particularly to the accompanying drawing 10 represents the barrel of the 40 gun, as a whole, the inner end of which is in the form of a single large tube, while the remaining portion, at the other end, is divided into two barrel portions 11, the same being connected together in spaced relation by the parallel longitudinal walls 12.

45 Between these walls there is located a channel 13 which communicates with the barrel portions 11 and the interior of the main larger barrel or breech portion 14. Engaged around the gun, at the inner end portions of the barrels 11, is a band 15 which strengthens the gun and prevents any tendency of the portions 11 to spread, when the gun is fired.

50 The projectile which is used in connection with the gun is clearly shown in Fig. 4.

This projectile includes a pair of explosive shot or bombs 16 which are connected by means of the chain 17. When the projectile is placed in the gun, the bomb portions 16 60 pass through the barrels 11 while the connecting chain passes through the channel 13. A metal carrier 18 is provided to engage around the chain, when said chain is doubled up, as seen in Fig. 6, to hold the 65 chain within a small and compact space. When the projectile is fired from the gun, the bombs pass out of the two barrels 11 while the doubled chain passes through the channel 13, but as soon as the projectile 70 leaves the mouths of the barrels 11 the bombs separate and break the carrier 18 so that the bombs will be disposed at the ends of the full length of chain. When this projectile strikes a wire entanglement the 75 chain will effectively cut through the wire. The projectile is also effective when it strikes the bow or other like projecting portion of a ship, the bombs being suddenly checked by the contact of the chain with the ship, 80 will fly inwardly against the sides of the ship and explode with the result that openings will be blown in both sides of the ship.

The shell used in connection with the chain shot is shown in Figs. 5 and 6, where- 85 in it will be seen that the shell is formed with a larger closed end portion 19 and the twin barrel portions 20, all formed and connected in the same manner as the barrel portions of the gun. The larger portion of 90 the shell holds the explosive while the portions 20 hold the shot 16 at the ends of the chain 17.

It will thus be seen that I have provided a novel and effective weapon of war, and one 95 which will effectively destroy a large number of the obstructions which would be encountered to prevent the proper and quick advance of troops.

The device is also effective as an anti-air- 100 craft gun, the chain and balls being adapted to destroy or so injure aircraft that they will be brought down and put out of use.

It will, of course, be understood that I do not limit the use of the subject-matter of this 105 invention to large caliber guns, but the use of the same principle in rifles, and other small arms, as well as in smaller pieces of artillery is well within the scope of the invention, and effectiveness of the device. 110

What is claimed is:

1. The combination with a gun having a

pair of spaced barrels, a firing chamber common thereto and a guide passage connecting the bores of the barrels throughout their lengths, of a carrier disposed within 5 the passage and slidable therethrough and from when released, and means for holding the carrier normally fixed, the carrier being adapted to contain the flexible connection between a pair of projectiles that may be 10 disposed within the barrels respectively.

2. A breech loading gun having a pair of spaced barrels, having a slot connecting the barrels throughout their lengths, and having a firing chamber with which communicate both barrels and the slot throughout its width.

3. A projectile for use in a twin barreled

gun including a shell including an explosive receiving portion, a pair of integral barrel portions connected together by a pair of 20 parallel walls, said barrel portions communicating with each other and with the explosive receiving portion, a projectile disposed in the shell and including a pair of explosive members, a chain connecting said 25 members, and a carrier for holding the chain temporarily in doubled condition within the shell.

In testimony whereof I affix my signature in the presence of two witnesses.

LUCKEY C. DAVIS.
